UNITED STATES PATENT OFFICE

2,568,575

MAGNETIC T SQUARE AND DRAFTING BOARD

Lester F. Wickman, Oakland, Calif.

Application October 24, 1949, Serial No. 123,275

1 Claim. (Cl. 33—76)

1

This invention relates to T-square construction for use in connection with drawing or drafting boards.

The primary object of the invention is to provide means for attracting and holding the head of a T-square against the guiding edge of a drawing board, thereby insuring a straight or perpendicular edge at all times, when the T-square assembly is being moved from the bottom edge of the drafting or drawing board, to the top edge thereof, or vice versa.

An important object of the invention is to provide means for insuring a uniform contact between the head of the T-square and drawing board at all times, without the necessity of the draftsman or person using the T-square, applying physical force to maintain a true contact throughout the length of the straight edge of the T-square head and the edge of the drawing board.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings:

Figure 1 is a fragmental elevational view of a drawing board, illustrating a T-square, constructed in accordance with the invention, as positioned thereon.

Fig. 2 is a rear elevational view of the T-square and one edge of the drawing board.

Fig. 3 is a sectional view taken on line 3—3 of Fig. 1.

Fig. 4 is a plan view illustrating the head of a T-square as equipped with a modified form of the invention.

Fig. 5 is a fragmental perspective view wherein one of the poles of the magnet is illustrated in block form.

Fig. 6 is a plan view wherein is shown the use of electro-magnets on a T-square head.

Fig. 7 is a diagram illustrating the circuits of the electro-magnet.

Referring to the drawing in detail, the reference character 5 indicates a drawing or drafting board, which is provided with a steel bar or armature 6 secured along one edge of the drafting board, as by means of the screws 7, that pass through the flange 8 which fits against the bottom of the drafting board adjacent to the edge thereof.

2

The reference character 9 indicates a T-square which is provided with the usual head 10 that contacts one edge of a drawing board when in use.

Secured to the inner edge of the head 10 is a magnet which comprises the bar 11, the ends of which terminate adjacent to the ends of the head 10. Pivotally mounted on the bar 11 adjacent to the ends thereof, are the rollers 12, the ends of the bar 11 being curved downwardly and inwardly towards each other so that the rollers 12 will contact the armature 6 at a point intermediate the upper and lower edges of the armature 6. The rollers embody high coercive force permanent magnets, one roller constituting the north pole of the magnet, while the other roller constitutes the south pole, to the end that the head of the T-square supporting the magnet will be drawn into close engagement with the armature 6, as the head is moved to bring the magnet into close contact with the edge of the drawing board.

This structure constitutes one which may be readily and easily applied to the usual drawing board and T-square, making use of permanent magnets as a means for holding a T-square in position against a drawing board.

In the form of the invention as shown by Fig. 4 of the drawings, the head 13 of this T-square, is provided with the magnet including a bar 14, block 15 formed integral with the bar and extending forwardly from one edge of the bar, and the block 16 which extends forwardly from the opposite end of the bar, the block 15 constituting the north pole of the magnet, while the block 16 constitutes the south pole of the magnet. This magnet cooperates with the steel bar 17 that is secured along one edge of the drafting board, indicated by the reference character 18.

In Fig. 6 of the drawing I have provided electro-magnets 19 and 20 which are disposed adjacent to the ends of the straight edge of the head 21 of this T-square, the electro-magnets 19 and 20 being in circuit with the source of electricity supply 22, which may be in the form of a battery, or the device may be plugged into the usual electric house circuit, through the wires 23 and 24, there being provided a switch 25 for controlling the circuit to the electro-magnets.

These electro-magnets cooperate with the steel bar 26 which is secured along one edge of the drawing board, and acts as the armature to cause the T-square to be attracted to the edge of the drawing board when the electric current is applied to the magnets.

From the foregoing it will be seen that due

to the construction shown and described, I have provided an attachment which may be used in connection with T-squares and drawing boards, for holding a T-square into close engagement with one edge of a drawing board to insure a straight or perpendicular edge at all times when moving the T-square assembly along one edge of a drawing board.

Having thus described the invention, what is claimed is:

The combination with a drawing board having an armature secured along a longitudinal edge thereof, of a T-square having a head providing a straight edge, a permanent magnet comprising a bar secured to the head of the T-square, the ends of the bar being curved downwardly and inwardly, magnet pole members embodying rollers secured to the downwardly and inwardly curved ends of the bar, cooperating with the

armature in holding the head of the T-square to one edge of the drawing board.

LESTER F. WICKMAN.
